(57) **CLAIM**

We claim the ornamental design for a storage unit, as shown and described.

DESCRIPTION

FIG. 1 is a front perspective view of the storage unit. FIG. 2 is a rear perspective view of the storage unit. FIG. 3 is a right side elevation view of the storage unit. The left side elevation view is a mirror image of the right side elevation view.

FIG. 4 is a front elevation view of the storage unit.

FIG. 5 is a top plan elevation view of the storage unit.

FIG. 6 is a bottom plan view of the storage unit; and, FIG. 7 is a rear elevation view of the storage unit.

The broken line disclosure of hardware is for illustrative purposes only and forms no part of the claimed design, and the broken lines shown on the four posts represent indeterminate height, and form no part of the claimed design.
